United States Patent Office

Des. 184,925
Patented Apr. 21, 1959

184,925

SHOWER STAND

Theodore Friend, San Francisco, Calif.

Application December 31, 1958, Serial No. 54,002

Term of patent 14 years

(Cl. D91—3)

Fig. 1 is a perspective view of a shower stand showing my new design;

Fig. 2 is a front view; and

Fig. 3 is a top view thereof.

I claim:

The ornamental design for a shower stand, as shown.
